MEANS FOR CLASSIFYING ROLLED BILLETS

Matthias Langen, Parkstone, England, assignor to
 The Loewy Engineering Company Limited,
 London, England, a corporation of Great
 Britain

Application March 31, 1945, Serial No. 585,991
 In Great Britain April 4, 1944

2 Claims. (Cl. 80—42)

1

According to common practice, billets rolled from one and the same ingot are divided into first and second qualities. The latter comprises those billets rolled from the top portion of the ingot, the material of which is not as sound and free from foreign matter as the bottom portion. In those cases where the ingot is introduced into the rolling mill with its top first, the second quality billets will be those which leave the mill first, and, conversely, where the billet is introduced with its top last, the second quality billets will be those which leave the mill last.

Previously, it was customary to separate the two categories of billets by manual means. This method was not found to be satisfactory, especially for modern continuous mills which are operated at high speeds and where the output of billets is very large.

It is an object of the present invention to provide a means for separating and classifying rolled billets which is capable of dealing with a large output of billets without appreciably impeding the flow of material through the rolling mill installation.

A rolling mill plant in which the classifying means according to the invention are incorporated will be described in detail below by way of example with reference to the accompanying drawings in which:

Fig. 1 is a plan view of the delivery end of a billet rolling mill plant showing diagrammatically the runout and delivery tables and the cooling bed, with the billet selecting means of the invention incorporated therein.

Fig. 2 is a section along line 2—2 of Fig. 1 showing on an enlarged scale one of a series of lifting elements which form part of the billet selecting means of the invention.

Fig. 3 shows the lifting elements of Fig. 2 in another working position.

Fig. 4 is a section along the line 4—4 of Fig. 2 showing the means for simultaneously operating a series of the lifting elements illustrated in Figs. 2 and 3.

Referring first to Fig. 1, it will be seen that the billets delivered from a train of rolling mill stands (not shown) are cut, while still hot, into suitable lengths by a flying shear 10, and are then passed on to a shear runout table 11. This table consists of a number of skewed rollers 12, so that the billets will be gradually shifted to one side of the table whilst travelling, and will thus form a close pack of billets alongside a series of guide rollers 14 arranged at one side of the table.

Arranged behind the runout table 11 and in

alignment therewith is a cooling bed approach table 15 consisting of a number of rollers 16. As shown in Fig. 1, the cooling bed may comprise two skid-beds 17 and 18 disposed side by side and practically identical with each other. The billets which lie on the rollers 16 may be transferred from there to one of the skid-beds 17 and 18 in the usual manner by means of chain or rope driven pusher dogs 19 (Figs. 3 and 4), the ropes or chains 20 being passed round sheaves 21 and driven from geared motors 22 through drums 23.

The admission of packs of billets from the shear runout table 11 to the cooling bed approach table 15 is regulated by a movable stop 24, further movable stops 24 being arranged at the ends of the two sections of the cooling bed approach table which are adjacent and co-extensive with the two skid-beds 17 and 18.

According to the invention, means are provided adjacent the cooling bed for separating certain billets of one pack from the rest before the latter are transferred to one of the skid-beds 17 or 18 for further treatment. One form which these means may take is shown more in detail in Figs. 2, 3 and 4; they include a series of lifting fingers 25 which can be raised from a position below the level of the table rollers 16 (Fig. 2) to a position above that level (Fig. 3). To this end, the fingers 25 are pivotally mounted by means of arms 26 on shafts 27 supported in bearings 28. Fixed to the shafts 27 are, furthermore, depending arms 29 which can be actuated in unison by a bar 30, whereby the arms 26 and 29, and thereby also the fingers 25, are rocked about the shafts 27. The bar 30 can be shifted by a piston rod 31 and a fluid-operated piston 32 moving inside a cylinder 33 pivoted to brackets 34.

As shown in Fig. 4, the sideguards 35 and the apron plates 36 of the roller table 15 are cut away so as to allow the lifting fingers 25 to pass therethrough during their rocking movement. It will be seen that the lifting fingers 25 are slightly inclined in order to facilitate the raising of the billets from the rollers 16.

The fingers 25, apart from their rocking movement, are further adapted to be shifted laterally for the adjustment of their throw. To this end, means are provided for moving the pivotal mountings 37 of the arms 26 along the shafts 27. These means comprise levers 38 engageable with a circumferential groove in the pivotal mountings 37 and adapted to be rocked about a common pivot 39 by means of a worm 40, the worm shaft 41 being rotated by a handwheel 42 through a vertical shaft 43 and a set of bevel gears 44.

It will be understood that the means for rocking the lifting fingers 25, and also those for shifting them laterally, can be modified and need not necessarily be of the type described in the preceding paragraphs.

In operation, billets rolled from one ingot, after having been cut to length on shear 10, are transported on to the shear runout table 11 where they are arrested by stop 24 and accumulate in one close pack at the offside of the shear runout table 11, due to the action of the skew rollers 12. It will be evident that the first billets of a batch will lie nearest the edge of the table, whilst the last ones will remain nearer to the centre. The stop 24 will then be withdrawn and the pack of billets conveyed to the cooling bed approach table 15 where they will be arrested by either the first or the second of the two stops 124.

In those cases where the ingots are rolled with their heads first, the first billets of a batch are likely to be of somewhat inferior quality as compared with the rest, for reasons set out before, and it is therefore desirable to separate them from the rest of the batch. This is achieved by means of the lifting fingers 25 which first are so positioned underneath the pack of billets by the afore-described lateral adjusting means 37 to 44 that they will just extend underneath the billets to be separated, but not further.

The fingers 25 are now actuated by the mechanism consisting of parts 26 to 32, whereby the second grade billets are raised from the rollers 16 and moved out of the way of the pusher dogs 19. Whilst these billets are in their elevated position, the remaining billets will be engaged by the pusher dogs 19 and transferred to one of the adjacent skid-beds 17 or 18. The lifting fingers are now lowered and the separated billets deposited again on the table 15 to be conveyed to a discharge table 45 and from there by means of a pusher beam 46 to a collecting grid 47 after the stop 124 by which the billets have been previously arrested has been withdrawn. Thus, the second grade billets will be diverted from the path taken by the rest of the billets.

It will be evident that the movement of the lifting fingers 25 has to be so timed with respect to that of the pusher dogs 19 that the second grade billets are raised from the rollers 16 before a set of pusher dogs 19 enters the spaces between the rollers 16, and that the billets have to be discharged from the table 15, after having been deposited thereon again, before the arrival of another set of pusher dogs 19. This timing can be achieved by suitably inter-connecting the control means for the lifting fingers and the pusher dogs.

The separation of the second grade billets takes place in the afore-described manner regardless of

whether the pack of billets has been previously arrested by the first of the stops 124 and thus come to rest at that section of the cooling bed approach table 15 which is adjacent the first skid bed 17, or whether the pack of billets has been previously arrested by the second of the stops 124 and thus come to rest on the section of the cooling bed approach table 15 which is adjacent the second skid bed 18. The only difference is that in the first instance the second grade billets on their way to the delivery table 45 have to pass first the section of the cooling bed approach table which is adjacent the second skid bed 18, whereas in the second instance the entire batch of billets will pass along the section of the cooling bed approach table 15 which is adjacent the skid bed 17, without the fingers 25 becoming active.

As a further alternative, a separate collecting grid 47 can be dispensed with, and the second grade billets transported either direct to the second skid-bed 18, in which case the first grade billets will be conveyed to the first skid-bed 17 only, or a separate third skid-bed of a design similar to that of the two skid-beds 17 and 18 can be provided for collection of the second grade billets.

The mechanism for operating the lifting fingers and the stops can be of any suitable design, and the invention is not limited to the special form shown in the drawings.

I claim:

1. Apparatus for classifying rolled billets prior to their transfer to a cooling bed, comprising means for forming a close pack of all the billets rolled from one batch, conveyor means for transporting the pack of billets to a point adjacent the cooling bed, means for transferring the billets from the said conveyor means to the cooling bed, means for temporarily lifting a predetermined number of billets situated on and near the edge of the pack so that they are out of reach of the said billet transfer means and means for transporting the previously withdrawn billets to a separate collecting station.

2. Apparatus for classifying rolled billets according to claim 1 in which the billet lifting means are adjustable in a direction across the pack of billets.

MATTHIAS LANGEN.
